Primary Examiner — Paula Greene(57) **CLAIM**

The ornamental design for a microphone boom for a communications headset, as shown and described.

DESCRIPTION

This application is related to co-pending U.S. Design application Ser. Nos. 29/547,974, titled "Communications Headset," and 29/547,980, titled "Communications Headset," both of which were filed Dec. 9, 2015.

FIG. 1 is a front-right perspective view of a microphone boom for a communications headset showing my new design;

FIG. 2 is a back-left perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines showing the unclaimed features form no part of the claimed design.

Further, the microphone boom for a communications headset is shown with symbolic break lines. The appearance of any portion of the article between the break lines forms no part of the claimed design.
